Primary Examiner — Susan E Krakower*Assistant Examiner* — Ramzi Almatrahi(74) *Attorney, Agent, or Firm* — Wolf, Greenfield & Sacks, P.C.(57) **CLAIM**

The ornamental design for a camera lens, as shown and described.

DESCRIPTIONFIG. 1 is a front, top and right side perspective view of a camera lens showing my new design;
FIG. 2 is a rear, bottom and left side perspective view thereof;
FIG. 3 is a front view thereof;
FIG. 4 is a top plan view thereof;
FIG. 5 is a bottom plan view thereof;
FIG. 6 is a right side view thereof; and,
FIG. 7 is a left side view thereof.

The broken lines depict portions of a camera lens in which the design is embodied and form no part of the claimed design. The dashed-dotted lines denote the boundary of the claim and form no part of the claimed design.
